Application July 8, 1947, Serial No. 759,488

8 Claims. (Cl. 294—115)

1

This invention relates to an automatic pin setter, and more particularly to a novel pin setting, search and pickup mechanism. This application is a continuation of our application Serial No. 748,158, filed May 15, 1947 now abandoned.

A general object of this invention is to provide improved pin setting, search and pickup mechanism in a pin setting machine.

An object of this invention is to provide in such a machine, improved means for setting pins through a pickup and search structure.

Another object is to provide an improved pin setting mechanism comprising a pair of parallel pickup bars operated by means of a novel self-locking arrangement.

Another object is to provide a pin setting and pickup mechanism which will accommodate worn pins or other pins having dimensions which deviate from a standard.

Another object is to provide a pickup mechanism wherein pins are clamped to the alley bed before they are picked up and re-set and when they are re-set the clamping pressure is not released until the pickup mechanism is completely clear of the pin.

Another object is to provide automatic pin setting mechanism in which the pins are not dropped but are set upon the alley bed before being released.

Other objects and advantages of this invention will be apparent from the following detailed description and from the drawings, in which:

Fig. 1 is a fragmentary perspective view of a bowling pin setting machine embodying a preferred form of the invention;

Fig. 2 is a perspective view of a single cell of the pin setter, parts of the apparatus being broken away to show underlying parts;

Fig. 3 is a fragmentary plan view of one of the grid structures utilized to support a portion of the apparatus of Fig. 2;

Fig. 4 is a side view of the structure shown in Fig. 3 showing the structure of the portion of one of the pin setting units which is supported thereby;

Fig. 5 is a partial plan view of another of the grid structures utilized to support a portion of the apparatus of Fig. 2;

Fig. 6 is a side view of the structure of Fig. 5 showing the structure of the portion of one of the pin setting units which is supported thereby;

Fig. 7 is a partial plan view of another of the supporting grid structures for the apparatus of Fig. 2;

2

Fig. 8 is a side view of the grid structure of Fig. 7;

Fig. 9 is an elevation of a latch and its associated mechanisms utilized to latch certain of the grid structures of Fig. 2 together;

Fig. 10 is an enlarged end view, partly in section, of a portion of the pin setting apparatus shown in Fig. 2;

Fig. 11 is a side view of the setting mechanism of Fig. 10 just after it contacts a pin standing on the alley bed;

Fig. 12 is a side view of the setting mechanism at an intermediate point in the operation of grasping a standing pin;

Fig. 13 is a side view of said apparatus at the completion of its operation of grasping a standing pin;

Fig. 14 is a side view of the pin setting and pickup apparatus at the start of an operation to set a new pin on the alley bed;

Fig. 15 is a side view of said apparatus just as a pin strikes the alley bed, and

Fig. 16 is a side view of said apparatus just after it has released the pin on the alley bed.

While we have illustrated in the drawings and shall herein describe in detail a preferred form of the invention, it is to be understood that the invention is not limited to the particular arrangement shown, it being contemplated that various changes may be made by those skilled in the art without departing from the spirit and scope of the invention as expressed in the appended claims.

As illustrated in the drawings, and with particular reference to Fig. 1, the preferred form of the invention is installed at the rear end of a bowling alley 20 equipped with the customary gutters 21 and 22 and pit 23. Pins 24 are arranged to be placed on the alley in the standard triangular formation of ten.

Generally, the machine comprises a tiltable tray 25 normally forming the bottom or floor of the pit 23 and inclinable to urge the pins and ball in the pit towards the rear against a pit cushion 26; a pin and ball elevating mechanism 27 having a plurality of pin and ball carrying flights 28 movable upwardly from the pit to a discharge position for the pins at 29; a ball transfer means 30 arranged to remove a ball 31 from the conveyor and transfer it to ball return tracks 32; a pin chute 33 for receiving pins discharged by the conveyor flights when tilted at 29; a rotary drum-like pin sorter 34 into which the pins pass from the chute 33 and are carried

upwardly for discharge into a distributor 35 com-

prising a plurality of chutes 36; a magazine 37 adapted to receive and hold a set of pins prior to their movement into a pinsetter 38 having ten vertically positioned and triangularly arranged pin tubes 39; a pin pickup mechanism 40 for elevating standing pins from the alley during a sweeping operation to remove dead wood therefrom, a sweep device 41 for sweeping the alley and gutters clear, a guard device 42 for stopping a ball thrown during certain operations of the machine, power operating mechanism including a power unit 43 and control mechanism housed partly in a unit 44. Shown also in Fig. 1 is a means for changing the pins in the machine by withdrawing the set that is in use and feeding into the machine an alternate set. This means includes pin containers or boxes 45 and 46, positioned generally under the parts 43 and 44 and a pin diversion chute structure 47 for diverting pins from the distributor 35 into one or the other of the boxes 45 and 46.

Preferably, the parts 30 to 47 inclusive are all supported on a carriage 48 which is movable from the normal rear position shown in Fig. 1 wherein the pin chutes 39 are over the respective pin spots on the alley 20, to a forward position approximately three feet ahead of the position shown in order to permit manual setting of pins on the alley by a pin boy. A walk 49, extending across the alley and any other alleys on which similar machines are installed to facilitate initial loading of pins into the machines or pin boxes and servicing of the power and control units, may be swung upwardly to a vertical position when the carriage 48 is to be moved forwardly. Generally, a masking unit or board 50 is located in front of the machine and at a suitable distance above the alley bed so as to shield the machine from the approach end of the alley. If desired, this masking unit may be equipped with signal lights arranged in a triangular formation similar to that of the pins on the alley and suitably connected to be illuminated when pins are standing.

The various machine parts will be described approximately in the sequence in which pins and the ball from the alley fall after a ball has been rolled down the alley by a player. Thus, upon such a rolling of the ball, the ball and usually some of the pins enter the pit 23 and rest upon the tray 25 in its lower or horizontal position. At such time the pin and ball elevator 27 is stopped in a position in which two of the flights 28 are below and behind the pit cushion 26 and the other two of the flights are above the top of the pit cushion so that it is impossible for the pins or ball to strike the elevator flights. The tray 25, as illustrated in Fig. 1 is in the form of a metal framework having a plurality of slots 60 in the rear edge thereof to accommodate the passage of forks or tines 61 on the conveyor flights. Preferably, the tray is covered with a layer 62 of a cushioning and sound deadening material such as rubber or felt. The tray is pivoted adjacent its rear edge on a cross shaft so that it may be moved from a lower horizontal position (which is assumed during actual bowling by a player) to the inclined or upper position illustrated, into which it is moved after a ball has been rolled. To swing the tray between its two positions, arms 64 extend rearwardly from the opposite side edges thereof and are slotted at 65 to admit a crank pin 66 carried on a cross shaft 67 which also supports the sprocket for operating the conveyor 27. In this manner, the move-

ments of the tray are synchronized with certain movements of the pin and ball conveyor.

The pin and ball elevator 27 comprises a pair of roller chains 68, one at each side of the pit 23 and each constrained to follow a special curved path by guide channels 69. Each guide channel has a rear portion through which the chain normally moves downwardly, a bottom portion through which the chain normally moves forwardly, and a forward portion through which the chain normally moves upwardly. The roller chains carry four tine assemblies or rakes which extend between the chains and consist of rods 28' and tines 61. The elevator flights or rakes are normally driven up through the slots 60 in the tray 25 to pick up pins and balls from below. Generally, a ball is picked up on the first flight of the conveyor passing upwardly from the tray and if not on the first flight, then almost invariably on the second. As soon as the first flight passes through the pins on the tray, the majority of the pins align themselves cross-alley and those which are not carried upwardly on the first flight are picked up on the second flight. The widely spaced tines effectively produce a "stringing out" or "debunching" of the pins, as only a limited number can get on one set of tines at one time. This avoids jamming of pins in the pin chute 33 when they are discharged from the elevator.

The chains 68 are driven from an upper cross shaft 70 which carries a sprocket 71 at each end thereof. The shaft 70 is rotatably supported on the frame 73 for the elevator and is connected to a drive shaft. Preferably, the drive shaft is driven by a reversible hydraulic or electric motor or other power means (not shown), the operation of which may be controlled automatically to give the pin and ball conveyor the desired movements.

The pit construction and the ball and pin elevator hereinbefore briefly described are disclosed more fully and claimed in our copending application Ser. No. 748,159 filed May 15, 1947.

The present invention is directed to a pin setting, search and pickup mechanism particularly adapted for use in a bowling pin setting machine of the type shown in Fig. 1, and which is disclosed more fully in our said copending application, or may be used in the pinsetter of the copending application of Jack Van Horn Whipple and Albert L. Odmark filed March 24, 1947, as Serial No. 736,632. Somewhat similar apparatus is also shown and described in the copending application of George A. Montooth filed March 24, 1947, as Serial No. 736,643. The apparatus of the present invention is shown in such a machine in Fig. 1, and is shown in greater detail in Figs. 2 to 10 inclusive. Figs. 11 to 16 show one unit of the mechanism in various operating positions during the operation of picking up a standing pin from the alley bed and setting a new pin on the alley bed.

The apparatus of this invention consists of a plurality of cellular structures mounted on a series of triangular grids or structural frames. These grids, five in number, are designated at 100, 101, 102, 103 and 104 in Fig. 2, and form parallel frames spaced vertically one above the other, and are capable of vertical motion relative to each other. The grids are all interconnected by a stop device which may comprise three vertical rods (not shown) extending through said grids and disposed near each of the corners thereof together with a series of stop collars and spacer members assembled in conventional man-

ner. By means of this stop device each adjacent pair of grids has a defined minimum and maximum separation. Since the grids are substantially rigid structures only three stops are necessary, one between each pair of grids, to define positively the spacial relationship of the grids.

Figs. 3 and 4 show the structure of grid 100, said grid comprising a generally triangular peripheral frame having side members 100a, a back member 100b and front member 100c and interconnecting members 100d, said interconnecting members extending between the side members transversely of the alley bed and between rows of pins thereon. These interconnecting members 100d act to transmit the weight of each pin setting unit cell as for example the cell shown in Fig. 2, out to the points of support on the side members 100a. Attached to the grid 100 are stop members 100e adapted to cooperate with the stop collars above mentioned in order to limit movement of the grid structure.

Within each of the ten openings provided on the grid structure, grid 100 carries a pressure plate assembly 110, said assembly being carried below the grid structure 100 by means of pins 111 and springs 112 so that said pressure plate is movable relative to the grid structure as will hereafter appear. A plurality of micro-switches 113 are carried by pressure plate supporting bars 114 which define the ten openings for the individual cells, these switches being adapted to be actuated by a movement of the pressure plate relative to grid 100, this movement being accomplished by clamping a standing pin to the alley bed against the resistance of the springs 112. A strike detector grid comprising bars 100f and 100g is also carried by the grid 100 to indicate through mechanism (not shown) the complete absence of pins after the rolling of ball so that a new set of pins may be set before a second ball is rolled.

Figs. 5 and 6 show in detail the construction of the second grid 101. This grid comprises a generally triangular structure having side members 101a, a back member 101b, a front member 101c and interconnecting members 101d extending transversely of the alley between the side members 101a. Stop members 101e are provided to limit the relative movement of the grid 101 with respect to the other grids as above described, and connecting members 115 are provided between the cross members 101d to define the openings for each of the individual cells.

Associated with each individual pickup unit or cell the grid 101 carries a search and pin pickup linkage structure indicated generally in Fig. 6 at 116, this structure being supported upon the grid by means of a supporting member 117.

In Figs. 7 and 8 the construction of the grid 102 is shown in detail. This grid is the only grid in the entire structure which is positively driven or moved (vertically), relative movement of the other grids being obtained by movement of this grid 102 while a pin 24 is clamped to the alley bed. The grid 102 is shown as comprising a generally triangular frame having side members 102a, a back member 102b, a front member 102c and transverse cross members 102d extending between such side members between the rows of pins. Stop members 102e are provided to cooperate with the stop device above described, and this grid is adapted to be positively driven both up and down by hydraulic or other means which are not shown here but which may be similar to the hydraulic drive arrangement shown in said

copending application of Jack Van Horn Whipple and Albert L. Odmark. Grid 102 is provided with a plurality of racks 120 supported on the side members 102a and front member 102c respectively by means of hanger brackets 121 connected to rack supports 122. The grid 102 carries search bar actuating members shown in Fig. 2 at 123, means for clamping the grids 102 and 100 (not shown), and means for receiving grid 103 (not shown).

Similarly grid 103 comprises a triangular structure carrying the pin setter mechanism to be hereafter described and also has means to locate grid 103 on grid 102, this means not being illustrated in detail.

Grid 104 which is shown only fragmentarily in Fig. 2 carries the distributor system 38 (Fig. 1) and the storage cells and release doors shown at the top of Fig. 2. This last mentioned grid 104 also has means for locking to grid 103 and stop apparatus of the same character as that shown in connection with grids 100, 101 and 102.

The operation of the apparatus disclosed herein can best be explained by combined reference to Fig. 2 and Figs. 11-16. For the purpose of this description it will be assumed that the first ball of a frame in a game of bowling has been rolled leaving at least one pin standing on the alley. During the bowling of this ball the grids are in an elevated position, the pressure plates 110 presenting a flat protective surface above the alley bed to prevent flying pins from striking the machine mechanisms. After the ball has been rolled, grid 102 (the only positively driven grid) is driven downwards. Grid 101 is suspended from grid 102 at a distance approximately 3½ inches, and grid 100 is suspended below grid 101 at a distance of approximately 5 inches. The pressure plates 110 extend below the top surface of grid 100 by about 3¾ inches, this arrangement providing that if a full sized bowling pin (about 15 inches high) is standing on the alley bed the pressure plate 110 will just contact the pin with grid 100 about 18¾ inches above the alley bed.

After this contact is made grid 102 is driven down about one inch farther, and since there is no change in the relative spacing between grids 100, 101 and 102, grids 100 and 101 also travel one inch lower so that grid 100 is now about 17¾ inches above the alley bed, and at this point the stops 100e strike collars (not shown) affixed to the machine frame, thereby preventing any further downward motion of the grid 100. Pressure plate 110, which preferably has its bottom surface covered with a resilient cushion 110a of rubber or some other material, has been stopped by the head of the bowling pin 24 and has compressed pressure plate springs 112 to apply a controlled pressure to the pin, holding said pin to the alley as shown in Fig. 11 (the pin 24 being broken off and shown only fragmentarily in Fig. 11 and subsequent figures). Standard sized bowling pins will cause a relative motion between the pressure plate 110 and the grid 100 of approximately one inch, and worn or shorter pins will cause less relative motion between said plate 110 and said grid 100. In one machine which we have constructed we have provided a structure capable of exerting necessary pressure in the event the bowling pin is as much as ¾ inch shorter than standard.

As shown in Fig. 11 the pressure plate 110 need not remain parallel to the grid 100, but is free to assume any position under the pressure of the four springs 112 at the corners thereof and

the head of the bowling pin 24, such bowling pin being illustrated in Figs. 10, 11, 12 and 13 as being moved a considerable distance away from its normal pin spot on the alley bed. In the event that the pin is on its normal spot, as is usually the case, the head of the pin will of course contact the pressure plate at the center thereof.

When the pin pickup apparatus has reached the position of Fig. 11 switches 113 which are carried on the support castings 114 (Figs. 2 and 3) are actuated by rods 125 which extend upwardly from the guide pins 111 within the springs 112 and from diagonally opposite corners of the pressure plate 110. By using a switch and actuating arrangement located above diagonal corners of the pressure plate at least one of the two diagonally placed switches will be actuated no matter how the pin is displaced. Switches 112 may be connected to a pin indicator circuit (not shown) to designate by lamps or other means which bowling pins were left standing after the first ball has been rolled.

At the other two diagonally opposite corners of the pressure plate 110 rods similar to the rod 125 extend upward and actuate one of the strike 25 detector grids 100_a or 100_b shown in Fig. 3, thereby serving to indicate that a strike has been made by the first ball if no rod is pushed up.

Referring now to Figs. 2 and 12, in Fig. 12 the grid 102 has moved down an additional distance of approximately 3 $\frac{1}{16}$ inches. Grid 101 moved down and stopped a distance of approximately 1 $\frac{1}{8}$ inches above grid 100. During this part of the cycle the search and pickup mechanism which is mounted on grid 101 is moved from its withdrawn position and lowered past the pressure plate 110 so that it is in the same horizontal plane as the head or neck of the clamped pin.

The pickup and resetting mechanism comprises a straight line linkage arrangement with a parallelogram-toggle locking linkage, there being two oppositely disposed sets of linkage associated with each individual unit or cell, although only one of said sets will be described here. Diagonally placed support members 130 are pivotally connected at their upper ends by means of rollers 130_a in vertical slots 131 in an upwardly extending portion 117_a of the support casting 117 which is secured to the grid 101, and the lower ends of each opposite member of each pair of members 130 are interconnected by a pin grasping bar 132, so that there is a pair of pin grasping bars extending horizontally and parallel to each other along opposite edges of the space within which the pin 24 is standing. Members 130 are connected intermediate their ends at 130_b to linking levers 133, these levers being fulcrumed at a point 133_a on a downwardly extending bracket 117_b which is integral with the support 117. The lower end of each of the levers 133 is pivotally connected to one of another pair of links 134 at 134_a, and the links 134 are pivotally joined together at their upper ends and joined to a single link 135 at 135_a, the other end of the link 135 being pivotally connected to an actuating rod 136. The actuating rod 136 is connected at its upper end to the actuating member 123 carried by grid 102, and said rod extends vertically through a guide opening in the member 117. As shown in Fig. 2, the support casting 117 may carry portions of the linkage for two adjoining pin pickup units.

Referring again to Fig. 12 it will be seen that as the apparatus moves from the position of Fig.

11, the parallel bars 132 have moved straight down below the level of the head of the pin, such bars maintaining their distance apart until they are at a pin grasping level. As the pin 5 grasping bars 132 are lowered, preferably a "dead area" detector grid (not shown) may be suspended from grid 101 and may be lowered ahead of all portions of the search bars 132. If a standing pin has moved from its normal spot a 10 sufficient distance so that it would be struck by the pickup mechanism as it descends, the dead area detector grid will strike said standing pin first. As grid 101 continues to move down, relative motion between said grid 101 and said detector grid may be caused to operate a switch which may be connected in a circuit arranged to stop the operation of the machine before damage occurs. For this purpose the grid structure 101 is permitted an additional motion of approximately one inch, and as said grid moves through this space the machine may be stopped by the action of the dead area detector grid.

Referring now to Fig. 13 grid 102 has descended approximately 1 $\frac{1}{8}$ inches from the position of Fig. 12. Since grids 100 and 101 have been stopped prior to this time, this last mentioned movement of grid 102 comprises a relative movement between grids 101 and 102. Such relative movement is transmitted through the cross bar 123 to move the actuating rod 136 downward, forcing the fulcrum of links 134 downward so that said links assume the position of Fig. 13. Levers 133 are caused to pivot about the point 133_a, and support members 130 carrying the bars 132 move toward each other at their lower ends so that each of the members 130 and each of the levers 133 are parallel to each other. Inasmuch as this linkage constitutes a differential arrangement, one or the other of said bars 132 30 will move in a horizontal line parallel to the alley surface until said pickup bar contacts the neck or head of the clamped bowling pin 24. This bar will then stop, but the opposite bar will continue to move until it contacts the pin, and the final part of the stroke of the actuating 35 rod 136 will act to straighten the links 134 so that the clamping action is locked with the bars 132 in operative position and the pin is gripped solidly by the parallel bars 132 and the pressure plate 110. We prefer to provide the bars 132 with a resilient surface covering, as for example rubber.

As the grid 102 descends to the position of Fig. 13 it is latched to the grid 100. A latch device which may be used for this purpose is 55 illustrated in Fig. 9, this device comprising a latch actuating member 140 pivotally affixed to the core 141_a of a solenoid 141, said core being constantly urged out of the solenoid by a spring 141_b. The latch actuating member 140 extends through a guide bracket 142 which is affixed to a latch member 143 having a latching end 143_a adapted to cooperate with a catch 144. The solenoid 141 and latching members 140 and 143 60 may be carried by the grid 102, while the catch member 144 may be carried by the lower grid 100, and descent of the grid 102 to the position of Fig. 13 causes operation of a switch (not shown) closing a circuit through the solenoid to pull the cord 141_a into the solenoid and move the latch into release position away from the catch 144.

After the bowling pin 24 has been clamped to the alley bed and grasped by the parallel bars 132, grid 102 is raised with grids 100 and 101 65 latched to it until grid 100 is approximately 29%

inches above the alley bed. A slight over-travel is permitted between grids 101 and 102 when said grids are in the position of Fig. 13 so that the locking latches shown in Fig. 9 have a self-locking action and will not release grid 100 even if the solenoid 141 is energized unless the bowling pin again touches the alley floor and the weight of grid 100 is taken away from the pickup unit and supported by the pressure plate 110 against the head of the bowling pin or by limit stops mounted on the frame of the machine. This arrangement avoids the necessity of accurately timing the energization of the solenoid 141 and insures that the pins will not be dropped to the alley bed, but will rest upon the alley bed before the clamping mechanism is released.

At the height of the upward travel of the pin pickup mechanism and the bowling pin, said bowling pin is approximately 12 inches above the alley bed, and the alley may be swept clear of fallen pins.

Grid 102 is now lowered to the position of Fig. 13, and during this lowering movement the solenoid 141 (Fig. 10) is energized, but release of grid 100 takes place only when the grid 102 has lowered sufficiently to set the base of the pin 24 on the alley bed. After the latch 143 is released the grid 102 is raised about $1\frac{1}{8}$ inches or until it just starts to pick up grid 101. During this movement the linkage device moves away from the head of the pin 24 to the position of Fig. 12, releasing the bowling pin 24, the pickup bars 132 moving horizontally away from the head of the bowling pin while the pressure on the head of the pin from the pressure plate 110 is retained. The bars 132 come to rest in their extreme open position of Fig. 12 and grid 102 is again raised. This time said grid 102 carries with it the grid structure 101 so that the linkage mechanism and bars 132 are lifted vertically into the spaces provided for them and the "dead area" detector grid (not shown) follows grid 101 upwardly so that said detector grid fills in the areas adjacent the pressure plates.

Grid 102 is raised an additional distance of approximately one inch, raising grid 100 to approximately $18\frac{3}{8}$ inches above the alley bed and lifting the pressure plate 110 away from the bowling pin 24. The lower surface of the pickup assembly now presents a flat surface in a horizontal plane above the alley bed with the respective pressure plates 110 and detector grids lying in the same horizontal plane so that a flat protective surface is presented to protect the mechanisms from flying pins when the next ball is rolled, and the bowling pins are now re-set on the alley in exactly the same position they occupied after the first ball was rolled.

The entire assembly may now be raised to a position well above the alley bed while the second bowling ball is rolled. After the rolling of the second ball if it is desired to provide an indication of the pins still standing, grids 100, 101 and 102 are lowered until grid 100 just reaches its lower limit stop where said grid is approximately $17\frac{3}{8}$ inches above the alley bed. This permits any standing pins to actuate pin indicator circuits through switches similar to switch 113 so that the indicator board shown in Fig. 1 at 50 will indicate the final count of pins standing.

Grids 100, 101 and 102 are now driven up to their upper limit of travel to receive a new set of pins while the sweep 41 clears the alley of all remaining pins. Grids 100, 101 and 102 are

raised until grid 100 is approximately $35\frac{1}{8}$ inches above the alley surface. During the last several inches of this stroke, the new set of bowling pins 24 which are carried by the setter grid 103, together with the rollers 150 (Figs. 2 and 14) are forced down through the pressure plate 110. In order to accommodate this operation the pressure plate 110 has a central cut out portion within which are mounted a pair of trap doors 110b and 110c as shown in Fig. 2. These trap doors are carried by spring loaded hinges 110d so that they may open downwardly when pressure is applied from above, but are prevented from opening upwardly by stops 151 carried on the pressure plate 110. We prefer to make the trap doors 110b and 110c of different sizes so that the dividing line between them is approximately $\frac{1}{2}$ inch off center. Since pins which are left standing on the alley bed are most often standing on their normal pin spots, this construction places the division line in the rubber cushion 110a which covers the bottom of the pressure plate trap doors away from the point of maximum wear. The detailed construction of the pressure plate assembly including the trap doors is shown in said copending application of Jack Van Horn Whipple and Albert L. Odmark and therefore will not be repeated here.

As the pins are delivered from the distributing mechanism 38 of Fig. 1 to the pin setting grid 103, grid 103 is latched to grid 104 by a pair of solenoid actuated latches similar to those shown in Fig. 9, the latches being carried by the upper grid 104 and the catches 144 being carried by the grid 103. When grid 102 has reached the upper limit of its travel approximately $1\frac{7}{8}$ inches below grid 103, a signal switch (not shown) may be actuated, closing a circuit to energize the solenoids 141 (Fig. 9) to release grid 103 from grid 104. Grid 104 is a storage grid with toggle-type doors 152 (Fig. 2) operable to retain extra pins. The arrangement is such that each door 152 in grid 104 will remain open until a bowling pin has dropped through the door into the corresponding pin setting cell of grid 104 and a switch (not shown) on each door is actuated as a pin drops through, said switch energizing a circuit to shut the door. When all doors on grid 104 are closed, a full set of ten pins is carried by the setter grid 103, and when this condition exists, but not until such condition exists, the location of grid 102 adjacent grid 103 will actuate latching solenoids 141 and release grid 103 from grid 104. Grid 103 is now carried by grid 102, being held thereon by gravity and the guiding action of the pin setting apparatus within each opening in grid 102. In the apparatus illustrated grid 102 must over-travel a slight distance, as approximately $\frac{1}{8}$ inch, to release the solenoid operated latches (Fig. 9), thus providing a self-locking arrangement wherein it is insured that grid 103 is resting on grid 102 before grid 103 is released from grid 104, so that said grid 103 can never drop in the space between grids 102 and 104.

The pin setting structure is now ready to be lowered, and in this position a standard size bowling pin 24 within the apparatus is approximately $27\frac{3}{8}$ inches above the alley, while an under-sized pin having a base diameter as much as $\frac{1}{4}$ inch below standard would be $27\frac{1}{2}$ inches above the alley bed, and such under-sized pin would not project below the lower edge of the trap doors 110b and 110c.

Grid 102 is now driven downward to the posi-

11

tion shown in Fig. 15. As this grid assembly moves downward from grid 104, the bowling pin 24 is held within the pin setter cell 155 by a pair of "clam shell" devices 156 which contact the pin at four points spaced 90 degrees from each other around the periphery of the pin so that the pin is properly centered within the cell 155.

The clam shell devices 156 are held open or closed by a toggle joint consisting of links 157 and 158 and a yoke 159. A spring 160 (Fig. 2) is so designed that it always urges the end of yoke 159 downward in a guide slot 161 carried by an extension 162 of the clam shell structure. When grid 103 was latched against grid 104 this downward motion was prevented by downward pressure on an actuating rod 163 which is pivotally affixed to the yoke 159 at 163a. This rod 163 is a telescoping rod having an internal pressure spring (not shown) contained within an enlarged telescoping portion 163b. Consequently the clam shells were held in closed position at the time the bowling pin 24 was dropped into position therein from the distributing apparatus 37. As soon as the bowling pin entered the clam shell, its weight forced it like a wedge into the clam shell. Toggle link 157 and yoke 159 are located slightly above the vertical center of the structure so that when the grid 103 dropped away from grid 104, the pressure of the actuating rod 163 no longer acted to overpower the springs 160. However the only way the springs 160 can open the clam shell is by pulling the link 157 and the yoke 159 through the center position, and the spring is unable to do this as the bowling pin within the structure is wedged against the clam shells and will not permit them to close the approximate $\frac{1}{8}$ inch necessary to permit this action. Consequently each bowling pin is held firmly in its clam shell cradle during the downward travel of the structure.

The stop system earlier described is mechanically interconnected with grid 103 in such a way that when grid 103 is released from grid 104 as the apparatus travels from the position of Fig. 14 to the position of Fig. 15, grid 100 is permitted to go down to a lower level which may be approximately $7\frac{1}{2}$ inches above the alley bed before striking a limit stop, and with grid 100 in this position the lowest portion of the open pressure plate doors 110b and 110c is approximately $\frac{1}{2}$ inch above the alley as shown in Fig. 15. While grid 100 remains in this position, grids 101, 102 and 103 continue to be lowered, and when the space between grids 101 and 100 is reduced to approximately $4\frac{5}{8}$ inches a normalized bowling pin will just touch the alley bed 20 as shown in Fig. 15. In this position the bowling pin is still clamped within the clam shell devices 156.

Referring now to Fig. 16, grids 101, 102 and 103 move downward an additional distance of approximately one inch. During this motion the pin setting mechanism and the dead area detector (not shown) will partially project below grid 100, but will not reach the closing position shown in Fig. 13, so they will not cause interference with the pin setting operation.

During this last described movement of approximately one inch, each bowling pin (including under-sized pins) will be set on the alley bed 20 and the clam shell devices 156 will continue to be closed and located straight down the sides of the pin until the toggle link 157, urged by the spring 160, moves downwardly past center position. When this happens the clam shells will

12

fly open symmetrically (due to the guiding action of the slot 161) and the pin within the apparatus will be set free on the alley. It will be noted that the bowling pin is set upon the alley while it is still clamped within the clam shells 156, so that at the time the pin is released there is no drop whatsoever to reach the alley, the base of the pin being guided at all times until it is set upon the alley bed and released.

10 The grid structure may now be raised, grids 101, 102 and 103 moving up until grid 100 is picked up by grid 101. Since the clam shell devices 156 are kept open by means of the springs 160 and since the clam shell devices hold open the trap doors 110b and 110c the entire unit may be 15 lifted without touching the standing pins 24. As grid 103 approaches grid 104, as for example within approximately $6\frac{1}{2}$ inches, the actuating rod 163 strikes grid 104, and as the rest of the 20 structure continues to move upwardly this rod applies pressure to the yoke 159, thereby closing the clam shells 156, and a closer approach of grid 103 to grid 104 is allowed by means of the telescoping action of the actuating rods 163, the portion 25 163b of said rods moving down over the inner portion 163.

Referring to Fig. 2, as the structure approaches its upward limit of movement, the upper end 165a of rocker arm 165 contacts a pivot rod 166 of the 30 toggle-lock door 152 on grid 104, and as the grids continue the last portion of their upward movement, the rocker arm 165 opens the door 152 by pressing upward against the force of a spring 35 (not shown) which normally tends to push the pivot rod 166 down and lock each door shut. As each door 152 is opened, any pin in storage above 40 will drop through, and if no pin is held in storage, the door will be held open until a pin is delivered from the distributor apparatus. As soon as a pin passes into the setter cell 155 of grid 103, the 45 largest portion of the pin strikes a roller 170 carried by the lower end of rocker arm 165, and actuates this rocker arm to pivot about its point of mounting 167 on the grid 103 so that the pivot pin 166 is released and the door 152 is permitted to close. This action prevents a second pin from coming through into the setter cell and also operates a switch (not shown) to indicate that that 50 particular cell is loaded and ready for another re-set operation.

Upon reaching the uppermost position, the sole-noid latches (Fig. 9) which are de-energized automatically latch grid 103 to grid 104.

We claim:

55 1. Bowling pin setting apparatus comprising, in combination, a pressure plate for clamping a pin in upright position, a pair of spaced parallel bars movable toward each other to grasp the neck of a clamped pin, a first vertically movable grid structure having a slot therein, means for supporting said bars for movement in a substantially horizontal plane comprising a pair of members pivotally and slidably mounted on said first structure in said slot, a second vertically movable grid structure, and means for operating said bars comprising an actuating member carried by said second structure, a pair of links pivotally connected intermediate their ends to said first structure and pivotally connected at one end to said respective supporting members intermediate the ends thereof, and a second pair of links interconnecting said first pair of links and said actuating member.

70 2. Bowling pin setting apparatus comprising, in combination, a lower grid structure having a

slotted upwardly extending portion and a downwardly extending portion, an upper grid structure, said structures being vertically movable together and with respect to each other, a pair of supporting members pivotally and slidably connected at one end to said lower structure in said slot and extending diagonally downwardly therefrom, a pair of pin grasping bars carried by said supporting members at the lower ends thereof, a first pair of links each connected at one end to one of said supporting members intermediate the ends thereof, and each pivotally connected intermediate their ends to the downwardly extending portion of said lower grid structure, an actuating rod carried by said upper structure, a second pair of links interconnecting said actuating rod and the other end of said first pair of links, said actuating rod operating said links upon relative movement between said grid structures to cause said bars to move from a withdrawn position to an operative pin grasping position.

3. Bowling pin setting apparatus comprising, in combination, a vertically movable frame, a pair of spaced parallel bars of substantial length, means for supporting said bars for movement in a substantially horizontal plane toward each other to grasp the neck of an upright pin comprising a pair of elongated supporting members each carrying one of said bars at one end thereof, said frame having means providing a substantially vertically slidable pivotal support for the other end of each of said members, and means for moving said bars including an actuating member movable relative to said pivotal support means, a plurality of links connecting the actuating member to each support member for providing a differential action in the movement of said bars, and at least two of said links being pivotally mounted on said frame.

4. Bowling pin setting apparatus comprising, in combination, a vertically movable frame, a pair of spaced parallel bars of substantial length, means for supporting said bars for movement in a substantially horizontal plane toward each other to grasp the neck of an upright pin comprising a pair of elongated supporting members each carrying one of said bars at one end thereof, said frame having means providing a substantially vertically slidable pivotal support for the other end of each of said members, and means for moving said bars including an actuating member movable relative to said pivotal support means, a first pair of links pivotally mounted on said frame and each pivotally connected at one end to an intermediate portion of a different one of the supporting members and a second pair of links each pivotally connected to the other end of a different one of said first pair of links and to the actuating member to provide a differential action in the movement of said bars.

5. Bowling pin setting apparatus comprising, in combination, a vertically movable frame, a pair of spaced parallel bars of substantial length, means for supporting said bars for movement in a substantially horizontal plane toward each other to grasp the neck of an upright pin comprising a pair of elongated supporting members each carrying one of said bars at one end thereof, said frame having means providing a substantially vertically slidable pivotal support for the other end of each of said members, and means for moving said bar including an actuating member movable relative to said pivotal support means, a first pair of links each pivotally connected at one end to an intermediate portion of a different one of the support-

ing members and a second pair of links each pivotally connected to the other end of a different one of said first pair of links and to the actuating member, and means on the frame providing a pivotal support for each of the first pair of links intermediate the ends thereof to provide a differential action in the movement of said bars.

6. Bowling pin setting apparatus comprising, in combination, a vertically movable frame, a pair of spaced parallel bars of substantial length, means for supporting said bars for movement in a substantially horizontal plane toward each other to grasp the neck of an upright pin comprising a pair of elongated supporting members each carrying one of said bars at one end thereof, said frame having means providing a pivotal support for the other end of each of said members, and means for moving said bar including an actuating member movable relative to said pivotal support means, a first pair of links each pivotally connected at one end to an intermediate portion of a different one of the supporting members and a second pair of links each pivotally connected to the other end of a different one of said first pair of links and to the actuating member, means on the frame providing a pivotal support for each of the first pair of links intermediate the ends thereof, and means for locking said bars in position grasping the neck of an upright pin.

7. Bowling pin setting apparatus comprising, in combination, a pair of spaced parallel bars of substantial length, means for supporting said bars for movement in a substantially horizontal plane toward each other to grasp the neck of an upright pin comprising a pair of elongated supporting members each carrying one of said bars at one end thereof, a first movable member provided with a pair of vertical slots, means slidably positioned in each of said slots and pivotally supporting the other end of each of said supporting members, a second member movable relative to the first movable member, a first pair of links each pivotally connected intermediate its ends to the first movable member and each pivotally connected at one end thereof to an intermediate portion of a different one of said supporting members, and means providing a toggle link connection between the other end of each of said links and said second movable member to provide a differential action in the movement of said bars with relative movement between the first and second movable members.

8. Bowling pin setting apparatus comprising, in combination, a pair of spaced parallel bars of substantial length, means for supporting said bars for movement in a substantially horizontal plane toward each other to grasp the neck of an upright pin comprising a pair of elongated supporting members each carrying one of said bars at one end thereof, a first movable member provided with a pair of vertical slots, means slidably positioned in each of said slots and pivotally supporting the other end of each of said supporting members, a second member movable relative to the first movable member, a first pair of links each pivotally connected intermediate its ends to the first movable member and each pivotally connected at one end thereof to an intermediate portion of a different one of said supporting members, a second pair of links each pivotally connected at one end thereof to the other end of a different one of said first pair of links and pivotally connected at their other end to said second movable member to provide a differential action in the movement of said bars with relative move-

15

ment between the first and second movable members.
